ATTORNEY

UNITED STATES PATENT OFFICE.

JOHN URBAN McDONALD, OF DECATUR, ILLINOIS.

FURNACE.

1,370,139.

Specification of Letters Patent.

Patented Mar. 1, 1921.

Application filed September 7, 1920. Serial No. 408,632.

To all whom it may concern:

Be it known that I, JOHN URBAN McDONALD, a citizen of the United States, and residing at Decatur, in the county of Macon 5 and State of Illinois, have invented a new and Improved Furnace, of which the following is a specification.

This invention relates to that class of furnaces in which metals are melted in pots or 10 crucibles and its object is to provide a furnace of maximum efficiency for the fuel consumed and which is especially adapted for the use of powdered coal as a fuel.

This invention consists of a furnace having a front wall extending upwardly to an arch provided with holes to permit the escape of the products of combustion, a rearwardly tapering combustion chamber spaced from said wall, and a fuel injector mounted 20 in said wall and extending partially across the space between the wall and the combustion chamber, the rear wall of the combustion chamber being constituted by two concave surfaces, preferably cylindrical.

It also consists in providing apertures in 25 the roof of the combustion chamber so that the crucibles may be lowered down onto the floor of said chamber and spaced apart from the walls and from each other to permit the 30 incandescent fuel and products of combustion to pass between the crucibles until the rear wall is reached and then rebound and pass forward around the crucibles to the front arch where they pass upward through 35 the openings therein.

It further consists in the details of construction illustrated in the accompanying drawing and particularly pointed out in the claims.

40 In the accompanying drawing, Figure 1 is a vertical central longitudinal section of this improved furnace. Figs. 2 and 3 are sections on the lines 2—2 and 3—3 of Fig. 1 respectively.

45 Similar reference characters refer to like parts throughout the several views.

The furnace shown in the drawing has side walls 1, a rear wall 2, a bottom 3 sloping down forwardly to the ash pit 4, and an 50 arched roof 5 which preferably slopes up from the rear wall 2 to the front arch 6. The roof 5 has openings 7 to admit the crucibles 8, which holes have covers 9. I prefer to form low pedestals 10 for the crucibles, 55 the height of these pedestals being determined by the pressure of the fuel feed and

the character of the fuel. Deflectors 12 are built out from the walls 1 and the inner surface of the rear wall is in the form of two half cylinders 13, divided by a deflector 14. 60

The powdered coal is forced through the pipe 15 into the furnace, preferably by means of highly heated air, the source of the air and coal not being shown. Because of this initial heat, the fuel burns at substantially the instant it leaves the pipe 15 with a very hot clear blue-white flame. The ash in the coal melts at once and flows down into the ash pit 4.

The intensely hot products of combustion 70 pass to the rear end of the furnace where they are split by the ridge 14, substantially one half passing around each rear crucible 8 and then forward around the forward crucibles, rising in the meantime and being 75 turned inwardly toward the pipe 15 by means of the deflectors 12. These gases then finally pass outwardly through the holes 16 in the arch 6. The heat carried away being utilized in any desired manner, 80 preheating another furnace preferred.

The pedestals 10 elevate the crucibles 85 from the floor into the zones of more intense heat. The fuel is ignited at the inner end of the pipe 15 and is burned almost completely by the time it reaches the forward crucibles, which are therefore subjected to intense heat on their inner sides, but the temperature of the products of combustion is still very high on the outsides of the forward crucibles. 90

The proportions and details of this furnace may all be changed by those skilled in the art without departing from the spirit of my invention as set forth in the following 95 claims.

I claim:—

1. In a furnace, a bottom sloping downwardly toward the front, a front wall, side walls, an arched top provided with holes to admit crucibles, a fuel pipe extending through the front wall, and a rear wall provided with a forwardly extending ridge to cause the products of combustion to divide and one-half to pass forwardly along each 105 side wall.

2. In a furnace, a bottom sloping downwardly toward the front, a front wall, side walls, an arched top provided with holes to admit crucibles, a fuel pipe extending 110 through the front wall, and a rear wall provided with a forwardly extending ridge to

cause the products of combustion to divide and one-half to pass forwardly along each side wall, the rear wall being concave between the ridge and each side wall.

- 5 3. In a furnace, a bottom sloping downwardly toward the front, a front wall, side walls, an arched top, a fuel pipe extending through the front wall, and a rear wall provided with a forwardly extending ridge 10 to cause the products of combustion to divide and one-half to pass forwardly along each side wall, the bottom being formed with pedestals to support crucibles which are spaced from the side wall and the top being formed with openings to admit the crucibles.

15 4. In a furnace, a bottom sloping downwardly toward the front, a front wall, side walls, an arched top, a fuel pipe extending 20 through the front wall, and a rear wall provided with a forwardly extending ridge to cause the products of combustion to divide and one-half to pass forwardly along each side wall, the bottom being formed with 25 pedestals to support crucibles which are spaced from the side wall and the top being formed with openings to admit the crucibles, said side walls being formed with inwardly extending deflectors between the 30 front crucibles and the front wall to cause the products of combustion to flow around the front crucibles.

35 5. In a furnace having a bottom, a top, side, front and back walls, said top having

openings to admit crucibles which are spaced 35 from the side walls, a fuel pipe extending through the front wall to direct fuel centrally of the furnace toward the back wall between the crucibles in the furnace, said back wall being formed with a central deflector to divide 40 the fuel and products of combustion and also formed concave on each side of the deflector to guide the products of combustion toward the side walls and forwardly so that the products of combustion will pass 45 between the side walls and the adjacent crucibles.

6. In a furnace, a front arch having openings in its crown to permit the escape of the products of combustion, a front wall, an ash pit below said arch, a heating chamber in the rear of said arch and ash pit and comprising side walls, an arched top, a bottom and a rear end wall, said top sloping down toward the rear and the bottom sloping 55 down toward the front, and the rear end wall being formed with a central vertical deflector and with a concave surface on each side to direct the products of combustion toward the front wall. 60

7. In a furnace, a bottom, a front wall, side walls, a top, a fuel pipe extending through the front wall, and a rear wall provided with a forwardly extending ridge to cause the products of combustion to divide 65 and to pass forwardly along each side wall.

JOHN URBAN McDONALD.
